EYE EXERCISING DEVICE

Lawrence G. Timeus, New York, N. Y., assignor to Timis Instrument Corporation, New York, N. Y., a corporation of New York

Application October 16, 1952, Serial No. 315,123

12 Claims. (Cl. 128—76.5)

The present invention relates to vision corrective orthopedic devices, and, more particularly, to a device for exercising the muscles of the human eye.

Heretofore, devices of the aforementioned character have been proposed, but these devices have met with indifferent commercial success for a number of reasons. Generally, such devices were in the nature of clinical apparatus adapted for rendering professional treatment, and consequently were unduly complicated and expensive. Since the muscles of the eyes should be exercised at frequent regular intervals to produce a beneficial result, for example, at least once or twice each day, the patient was required to make many visits for treatment. This was not feasible because it consumed considerable time on the part of the patient, and because physicians and clinics have limited visiting hours, thus making regular treatment impossible. On the other hand, very few patients could afford to purchase such devices for self treatment at home due to their expensiveness, and, even if a patient possessed such a device, its size and complicity made it difficult to transport the same in the event the patient was required to travel.

Accordingly, an object of the present invention is to provide a device for exercising the muscles of the human eye which is not subject to any of the foregoing difficulties and disadvantages.

Another object is to provide such a device which is relatively inexpensive and can be afforded by anyone requiring treatment.

Another object is to provide such a device which is constructed of a minimum number of simple, lightweight parts which can be placed in a small box adapted to be carried about conveniently by the user.

Another object is to provide such a device which does not have any parts requiring replacement or repair.

Another object is to provide such a device which can be assembled and used without any skill on the part of the user.

A further object is to provide such a device which can be manipulated with one hand.

A still further object is to provide such a device having adjustable elements for varying the exercises which the eye muscles are given.

Other and further objects of the invention will be obvious upon an understanding of the illustrative embodiment about to be described, or will be indicated in the appended claims, and various advantages not referred to herein will occur to one skilled in the art upon employment of the invention in practice.

In accordance with the invention, the foregoing objects and their attendant advantages are attained by providing an eye exercising device which comprises a shaft, a member on one end of the shaft having a portion of a shape to receive and engage the nose of the user of the device, a rotor rotatably and slidably mounted on the shaft having indicia adapted for visual observation to focus the eyes of the user thereon, and manually engageable means on the rotor for effecting rotative and sliding movement of the rotor with respect to the shaft. In the illustrative embodiment about to be described, the position of the indicia on the rotor may be adjusted, and the rotor may have a scale thereon for indicating the position of the indicia. Likewise, the shaft may have a scale thereon for indicating the position of the rotor whereby the device is rendered adjustable.

A preferred embodiment of the invention has been chosen for purposes of illustration and description, and

2

is shown in the accompanying drawing, forming a part of the specification, wherein:

Fig. 1 is a perspective view illustrating a device in accordance with the invention in actual use.

Fig. 2 is a sectional view taken along the line 2—2 on Fig. 1, illustrating one manner of adjustably positioning the indicia on the rotor.

Fig. 3 is a top plan view illustrating the shaft and rotor in dismantled relation and arranged compactly in a small box for storing the same.

Referring to the drawing in detail, and more particularly to Fig. 1 thereof, there is shown a device for exercising the muscles of the human eye which essentially comprises a shaft 10 and a rotor 11.

The shaft 10 is in the form of an elongate rod or tube of a circular cross-section having a member 12 attached to one end thereof which facilitates supporting the shaft on the nose of the person using the device.

The member 12 includes a portion 14 formed with an aperture 15, such as a sleeve portion, for threadedly or adhesively securing the end of the shaft therein; and includes a portion 16, such as an arcuate strip, which has a surface shaped to receive and engage the bridge of the nose. If desired, the strip portion may be formed of bendable or yieldable material adapted to be shaped to conform to the contour of the nose of the user.

The rotor 11, as shown herein, is in the form of an elongate member disposed perpendicular with respect to the shaft 10 and mounted for rotative and sliding movement thereon. While the rotor may be in the form of a disc, a narrow strip-like rotor is preferred to reduce the size and weight thereof to a minimum and to provide for compact packaging as will be made apparent hereinafter.

Preferably, the rotor has a plurality of balanced arms, for example, a pair of opposed arms 17, to facilitate rotation of the rotor on the shaft, and has manually engageable means 19, such as a sleeve or tubular section through which the shaft extends, for effecting rotative and sliding movement of the rotor with respect to the shaft. The distance between the end of each arm and the shaft is greater than the distance between the bridge of the nose and the outer corner of the eyes of the user.

One of the arms 17 has indicia 20 thereon shown as a circular element adapted for visual observation to focus the eyes of the user thereon. This element is opaque, whereas the arms of the rotor may be formed of a transparent material, preferably a crystal clear synthetic plastic material because of its unbreakability in normal use, whereby the arms are practically invisible and do not detract from concentrating on the indicia.

In order to render the device adjustable for various focal distances of the indicia, the rotor is slidable lengthwise along the shaft as already mentioned, and the indicia is removably attached to the rotor in any suitable manner to position the same at different distances from the shaft. One manner of accomplishing this in a simple and convenient manner is to secure the indicia element 20 to the rotor by means of pressure sensitive adhesive 21 (Fig. 2).

Accurate positioning of the indicia at prescribed distances, lengthwise and radially, is made possible by providing a scale on the shaft 10 and a scale on the edge of the rotor, respectively.

In using the device as shown in Fig. 1, the indicia is positioned on the rotor at a prescribed distance from the shaft, and the rotor is positioned on the shaft at a prescribed distance from the eyes of the user. The nosepiece 16 is placed on the bridge of the nose of the user, and the free end of the shaft and the sleeve 19 are grasped by one hand of the user in a manner to support the device and enable at least two fingers to manipulate the rotor to effect rotation thereof. The eyes are focussed on the indicia, and the rotor is turned slowly about the shaft, thus causing the eyes to follow the indicia along its circular path whereby the muscles of the eyes are exercised in the course of following the indicia.

In Fig. 3, the device is shown with the rotor and shaft taken apart or dismantled and placed in the bottom part 25 of an elongate, narrow, shallow box adapted to receive a cover (not shown). In this manner, the device can be packaged and stored in a compact arrangement which facilitates merchandising the same and which enables the

user of the device to carry the same in a convenient manner on the person or in a handbag.

From the foregoing description, it will be seen that the present invention provides a simple, practical and inexpensive eye exercising device which is small in size, light in weight and readily portable, but yet is sufficiently rugged in construction to withstand such rough usage to which it normally may be subjected.

As various changes may be made without departing from the spirit and scope of the invention and without sacrificing any of its advantages, it is to be understood that all matter herein is to be interpreted as illustrative and not in any limiting sense.

I claim:

1. An eye exercising device comprising a shaft having a cylindrical section, a member on one end of said shaft having a portion of a shape to receive and engage the nose of the user of the device, a rotor formed with a cylindrical bore for receiving said shaft section rotatably and slidably mounted on said shaft section having indicia adapted for visual observation to focus the eyes of the user thereon, and manually engageable means on said rotor for effecting rotative and sliding movement of said rotor with respect to said shaft.
2. A device according to claim 1, wherein said rotor is transparent and said indicia is opaque.
3. A device according to claim 1, wherein said shaft has a scale thereon for indicating the distance between said rotor and said member.
4. A device according to claim 1, wherein said rotor has a scale thereon for indicating the distance between said indicia and said shaft.
5. A device according to claim 1, wherein said indicia is removably secured to said rotor to position the same on said rotor at various distances from said shaft.
6. A device according to claim 5, wherein said rotor has a scale thereon for indicating the distance between said indicia and said shaft.
7. An eye exercising device comprising a shaft having

4

5 a cylindrical section, a member on one end of said shaft having an arcuate surface adapted to receive and engage the bridge of the nose of the user of the device, a tubular sleeve formed with a cylindrical bore for receiving said shaft section to rotatably and slidably mount said sleeve on said shaft section, an elongate member integral with said sleeve and substantially perpendicular with respect to said shaft, and indicia on said last mentioned member adapted for visual observation to focus the eyes of the user thereon.

10 8. A device according to claim 7, wherein said first mentioned member includes a sleeve portion formed with an aperture at one end for receiving said shaft and securing the same therein and includes a strip on said sleeve portion at the end opposite said aperture which provides

15 said arcuate surface.

9. A device according to claim 7, wherein the distance between one end of said elongate member and said shaft is greater than the distance between the bridge of the

20 nose and the outer corner of the eyes of the user.

10. A device according to claim 7, wherein said elongate member has a plurality of balanced arms to facilitate

rotation of said elongate member on said shaft.

11. A device according to claim 7, wherein said elongate member has a pair of opposed arms of equal length

balanced for rotation on said shaft.

12. A device according to claim 11, wherein said arms

are transparent and said indicia is opaque and is positioned on one of said arms.
